UNITED STATES PATENT OFFICE.

JAMES J. McMULLEN, OF BUFFALO, NEW YORK, ASSIGNOR TO CORA SMITH, OF BUFFALO, NEW YORK.

HORSESHOE.

1,280,791.

Specification of Letters Patent.

Patented Oct. 8, 1918.

Application filed January 23, 1915, Serial No. 3,927. Renewed January 21, 1918. Serial No. 213,102.

To all whom it may concern:

Be it known that I, JAMES J. McMULLEN, a citizen of the United States, residing at Buffalo, in the county of Erie and State 5 of New York, have invented new and useful Improvements in Horseshoes, of which the following is a specification.

This invention relates to an anti-slipping horseshoe of the type having a calk plate 10 separate from the usual horseshoe, and more particularly to a cushioned shoe of this kind.

One of the objects of the invention is the production of a comparatively light and inexpensive shoe of this character having a calk-plate which permits the shoe to be widened or narrowed within limits to fit 15 hoofs of different sizes.

A further object is the provision of 20 elastic heel portions to relieve the animal from shocks and jars.

In the accompanying drawings:

Figure 1 is a side elevation of the shoe applied to the animal's hoof. Fig. 2 is a 25 top plan view thereof. Fig. 3 is a bottom plan view with one of the rubber pads omitted. Fig. 4 is a transverse vertical section on line 4—4, Fig. 3. Figs. 5 and 6 are longitudinal sections on lines 5—5 and 6—6, 30 respectively, of Fig. 3. Fig. 7 is a perspective bottom view of the calk-plate.

Similar characters of reference indicate corresponding parts throughout the several views.

1 indicates the horseshoe fastened to the animal's hoof by the usual nails and having the customary toe clip 2, but no calks. In place of such calks a separate calk-plate 3 is employed. This plate is preferably 35 channeled to form downwardly-projecting flanges 4 and 5, the outer flange 4 being notched in its lower edge to form non-slipping calks or teeth 6. This calk-plate has the general contour of the horseshoe, but is 40 preferably somewhat narrower than an average sized shoe. The front portion 7 of the outer flange 4 is so shaped as to form practically the front calk of the shoe. The heel portions of the inner and outer flanges 45 4 and 5 are united by integral curved portions 8, and the web or horizontal top portion of the calk plate terminates short of the rear ends of said flanges, leaving openings 8a.

The toe portion of the calk-plate is preferably fastened permanently and immovably to the toe portion of the horseshoe by rivets or other means 9. A boss or projection 10 extends downwardly from the toe portion of the shoe into a recess 11 formed 55 in the toe portion of the calk-plate to relieve the rivets 9 from undue strain. This boss may be oval, as shown, or of any other suitable form. The heel portions of said plate are attached to the corresponding portions of the horseshoe preferably permanently, but in such a manner as to allow limited longitudinal play or adjustanment of the heel portions of the calk-plate on the heel portions of the horseshoe, in order to 60 permit the shoe to be widened or narrowed relatively to the calk-plate to fit different sized hoofs. The preferred connections or fastenings shown in the drawings for this purpose consist of pins or rivets 12 secured 65 to the horseshoe and passing through longitudinal slots 13 formed in the heel-portions of the calk-plate. These rivets are originally located centrally in said slots, so that the shoe will fit an average-sized hoof. 70

In order to narrow the shoe to fit a hoof below the average size, the blacksmith places one side of the shoe edgewise on the flat-portion of the anvil and gives it a few blows with a hammer to contract it to the 75 desired size, the slots 12 permitting the necessary longitudinal movement of the heel portions of the shoe on those of the calk-plate, as before described. If the shoe is to be widened to fit a hoof above the average 80 size, its heel portions are spread to the necessary extent by placing them over the horn of the anvil and giving the toe of the shoe a number of blows.

To reinforce the walls of the heel portions of the plate and prevent collapse or crushing thereof during this spreading operation, the shoe 1 is provided on the underside of its heel portions with transverse ribs or braces 14 which project into the openings 8 of the calk plate and are of the proper length to bear against their side walls.

By the provision of such sliding connections between the calk-plate and the horseshoe, a calk-plate of a given size is applicable to different-sized horseshoes or to a shoe of given size which is expanded or contracted to fit different sized hoofs, thus 105

avoiding the necessity of manufacturing the calk-plates in a large variety of different sizes.

As shown at 15 in Fig. 1, the heel portions 5 of the shoe are preferably recessed or cut away on their under side to leave spaces between the shoe and the calk-plate at these points which permit a spring action of said heel portions which greatly relieves the animal 10 from the shock and jar incident to travel. To furnish further relief in this respect and prevent slipping, the heel portions of the calk-plate may be provided with rubber pads or cushions 16 which are molded 15 around the rear portion of the calk-plate and shoe and which may also be interposed between the recessed heel-portions of the shoe 20 and the calk-plate, as shown in Fig. 1. To anchor the cushions, the heel-portions of the calk-plate may be provided with undercut notches 17 and the shoe with slots 18.

19 indicates a shield or covering which is placed over the upper side of the calk-plate to close the central opening thereof and prevent snow from balling up under the animal's hoof. This shield conforms to the general contour of the inner edge of the horseshoe, as shown in Fig. 2, and preferably consists of a layer of canvas coated with rubber 30 on both sides. This shield and the rubber pads 16 may be vulcanized to the shoe and the calk-plate at the same time.

The calk-plate as well as the rubber pads or heel portions prevent slipping of the animal, while the pads together with the recessed or reduced heel portions of the shoe 35 relieve the animal from jars upon hard pavements. While possessing these advantages, the shoe is not unduly heavy, and it can be 40 produced at relatively small cost.

By constructing the calk-plate separate from the shoe, the plate can be tempered to give its flanges the necessary strength to remain intact and not bend over and its teeth 45 the necessary hardness to remain sharp and not become battered or burred, while at the same time the plate has the requisite flexibility to permit expansion and contraction of its heel portions with those of the main shoe 50 in fitting the same to the animal's hoof.

I claim as my invention:

1. A horseshoe comprising a shoe and a calk-plate of approximately horseshoe form,

fastening means for holding the toe-portions of said parts against relative movement 55 lengthwise of the horseshoe, and means connecting the heel portions of the shoe and the calk-plate and permitting longitudinal movement of the heel-portions of the shoe relative to the heel-portions of the calk-plate, in expanding or contracting the sides 60 of the shoe to fit different-sized hoofs.

2. A horseshoe comprising a shoe having pins projecting from its heel portions, and a calk-plate having its toe portion secured to 65 the toe portion of the shoe and provided in its heel portions with longitudinal slots in which said pins are arranged to slide in expanding or contracting the sides of the shoe. 70

3. A horseshoe comprising a shoe and a channeled calk-plate of approximately horseshoe form, a flange of said plate being provided in its lower edge with teeth, means for fastening the toe-portions of said 75 shoe and plate together, and means connecting the heel-portions of said shoe and calk-plate and permitting longitudinal movement of the heel-portions of the shoe relative to the heel-portions of the calk-plate. 80

4. A horseshoe comprising a channeled metallic calk-plate of approximately horseshoe form and with the rear portions of its web cut away between the depending flanges of the plate, a shoe having its heel-portions 85 provided with braces extending downwardly between said flanges, and means for securing said calk-plate to said shoe.

5. A horseshoe comprising a channeled calk-plate of approximately horseshoe form, 90 the web of the plate terminating short of the rear ends of its depending flanges, and a shoe having its heel portions provided with transverse ribs projecting downwardly between the heel portions of said flanges in 95 rear of said web, the toe portions of said shoe and calk-plate being fastened together, while the heel portions of the shoe are movable lengthwise on the calk-plate.

Witness my hand this 20th day of January, 1915. 100

JAMES J. McMULLEN.
